UNITED STATES PATENT OFFICE.

JOHN WALTER FINCH, OF ELIZABETH, MISSISSIPPI.

LOCOMOTIVE.

No. 861,101.

Specification of Letters Patent.

Patented July 23, 1907.

Application filed March 9, 1906, Serial No. 305,083. Renewed December 24, 1906. Serial No. 349,360.

To all whom it may concern:

Be it known that I, JOHN WALTER FINCH, a citizen of the United States, and a resident of Elizabeth, in the county of Washington and State of Mississippi, have 5 invented certain new and useful Improvements in Locomotives, of which the following is a specification.

My invention is an improvement in locomotives, and consists in certain novel constructions and combinations of parts hereinafter described and claimed.

10 Referring to the drawings forming a part hereof Figure 1 is a side elevation of a locomotive provided with my improvement. Fig. 2 is a detail view of the reversing mechanism. Fig. 3 is a plan view of a part of the locomotive frame. Fig. 4 is a front view of the 15 arm and pinions, and Fig. 5 is a side view of the same, partly in section.

In the present embodiment of my invention the locomotive A rests upon the frame *a* upon which are journaled shafts *b* in the usual manner, the said shafts 20 being provided upon the ends with drive wheels B.

The drive wheels B are provided at their peripheries on the outer sides thereof with internal racks *b'*, and upon the extended ends of the shafts *b* are secured pinions *b*², the said pinions being rigid with the shafts 25 and with the drive wheels B.

Arms *b*³, are journaled upon the shafts outside the pinions, the said arms being provided with a longitudinal slot *b*⁴ in which is slidably mounted a block *b*⁵ having journaled therein a stud shaft *b*⁶ to which is 30 rigidly secured upon the inner side of the arm, a gear wheel *b*⁷ adapted to mesh with the rack or with the pinion as may be desired.

A connecting rod *b*⁸ is rigidly connected with each of the stud shafts upon the outer side of the arm, the 35 said connecting rod being connected by a link *b*¹⁷, with the cross-head *b*¹⁵, movable in guides *b*¹⁶, and connected in turn to the piston rod *b*¹⁴ of the piston *b*¹³, movable in the cylinder *b*¹⁰.

Above the cylinder *b*¹⁰ is a steam chest *b*¹¹ containing 40 the usual valve mechanism *b*¹². The valve mechanism upon each side of the locomotive is connected by a link *c*¹⁰ to an upwardly projecting arm *c*⁸ of the rock shafts *c*⁷ journaled in brackets *c*¹⁴ upon the frame. Downwardly projecting arms *c*⁹ of the rock shaft *c*⁷ are 45 provided with blocks *c*⁶ upon which slides a link *c*⁵, the said link being movable upon the block by means of the link *c*⁰, connected to one arm *c*¹⁵ of the rock shaft *c*¹² journaled in brackets *c*¹³ upon the frame, and rocked by means of a reverse lever *c*¹⁷ connected by a 50 link *c*¹⁶ with the upwardly projecting arm *c*¹⁵ of the rock shaft. The shaft *c*¹² is provided at approximately the center thereof with a crank arm *c*²⁵ connected by a rod *c*²⁶, with a lifting spring *c*²⁷ secured to the frame whereby to assist in manipulating the reverse lever.

55 A supernumerary shaft C having cranked ends *c* provided with wrist pins *c'* journaled in the connecting

rods *b*⁸, is suitably journaled upon brackets on the frame, the said shaft being preferably arranged between the front axle and the one immediately following it, and with the cranked ends projecting beyond the 60 outer face of the wheels.

Upon the shaft are eccentrics *c*³ encircled by straps *c*⁴ connected by rods *c*¹⁸, with the links *c*⁵ in the usual manner. The above described mechanism is the usual reverse mechanism of the ordinary locomotive but having the eccentrics for operating the valve mechanism arranged upon the supernumerary shaft instead of upon one of the shafts of the driving wheel.

Any suitable means may be provided for moving the sliding block *b*⁵ in the slot *b*⁴, whereby to bring the 70 gear wheel in mesh with the pinion or with the internal rack. In Figs. 4 & 5 I have shown a form of said mechanism comprising a setscrew *b*¹⁸ traversing a screw-threaded opening in the end of the arm and pivotally connected with the block.

75 In operation when high speed is desired, the block is moved in the slot to bring the gear wheel into contact with the pinion, while when low speed with greater power is desired, the block is moved to bring the same in mesh with the internal rack. Since the gear wheel 80 is rigid with the connecting rod, it must rotate the drive wheel in the same direction with the revolution of the connecting rod. When the gear wheel is placed in a position intermediate the rack and pinion, the driving mechanism is entirely out of engagement with 85 the drive wheel, which may rotate freely without producing any wear upon the cylinder and valve mechanism.

It will be evident from the description that a much 90 higher speed is attained by the same consumption of fuel and without increasing the number of strokes of the piston.

Having thus described my invention, what I claim as new and desire to secure by Letters Patent is—

1. In a locomotive, the combination with the frame, of 95 shafts journaled in the frame, drive wheels secured to the shafts, pinions secured to the shafts, outside the drive wheels, longitudinally slotted arms journaled on the shafts outside the pinions, blocks movable in the slots, set-screws traversing the arms and engaging the blocks whereby to move the same, stud shafts journaled in the blocks, gear wheels rigid with the stud shafts on the inner side of the blocks and adapted to engage the pinion on the drive wheel shaft, a connecting rod rigid with the stud shafts on the outer side of the blocks, cylinders supported on the frames, 100 valve mechanism for controlling the admission of steam to the cylinders, pistons in the cylinders, connections between the pistons and the connecting rods, a supernumerary shaft journaled on the frame and provided at each end with cranked portions having wrist pins engaging the connecting rods, eccentrics on the supernumerary shaft, straps on the eccentrics, a movable link, rods connecting the ends of the link to the straps, a connection between the link and the valve mechanism, and means for moving the link to 105 control the valve mechanism.

2. In locomotives, the combination with the frame, of 110

shafts journaled in the frame, drive wheels having internal racks secured to the shafts, pinions secured to the shafts outside the drive wheels, arms journaled on the shaft outside the pinions, a block slidably mounted on each of the 5 arms, a stud shaft journaled in the block, a gear wheel rigid with the stud shaft on one side of the block, a connecting rod rigid with the stud shafts on the other side of the block, means for moving the blocks whereby to move the gear wheel into mesh with the internal rack or the 10 drive shaft pinion, means engaging the connecting rods for driving the shafts, a supernumerary shaft journaled in the frame and having cranked ends engaging the connecting rods, and reversing mechanism connected with the shaft.

3. In a locomotive, the combination with the frame, of 15 shafts journaled on the frame, drive wheels having internal racks secured to the shafts, pinions secured to the shafts outside the drive wheels, arms journaled on the shafts outside the pinions, stud shafts slidably mounted in the arms, gear wheels rigid with the shafts on the inner 20 ends of the arms, a connecting rod rigid with the stud shafts on the outer side of the arms, means connected with the connecting rod for actuating said rod to rotate the arms, and means whereby to move the stud shaft into mesh with the pinion or the internal rack.

4. In a locomotive, the combination with the frame, of 25 shafts journaled on the frame, drive wheels secured to the shafts, arms journaled on the shafts outside the drive wheels, a rod connecting the arms upon each side of the frame, means on the arms for engaging the drive wheels 30 whereby to rotate the same, and means for moving said engaging means radially to the drive shafts whereby to engage said wheels at different distances from their center.

5. In a locomotive, the combination with the frame, of 35 shafts journaled in the frame, drive wheels rigid with the shafts, means for driving the wheels normally out of engagement therewith, and means for actuating said driving means to engage the wheels at different distances from the center thereof.

6. In a locomotive, the combination with the frame, of 40 shafts journaled on the frame, drive wheels secured to the

shafts, arms journaled on the shafts outside the drive wheels, a rod connecting the arms upon each side of the frame, means on the arms for engaging the drive wheels whereby to rotate the same, means for moving said engaging means radially of the shafts whereby to engage said 45 wheels at different distances from their centers, cylinders having pistons connected to the connecting rods, valve mechanism for the cylinders, a supernumerary shaft journaled on the frame and having cranked portions engaging the connecting rods, and means connected with the shaft 50 for controlling the valves.

7. In a locomotive, the combination with the frame, of shafts journaled in the frame, drive wheels rigid with the shafts, means for driving the wheels normally out of engagement therewith, means for actuating said driving 55 means to engage the wheels at different distances from the center thereof, a supernumerary shaft, a connection between the driving means and the supernumerary shaft whereby to rotate the same, cylinders having pistons connected with said driving means, valve mechanism on the 60 cylinders, and a connection between the supernumerary shaft and the valve mechanism for controlling the same.

8. In a locomotive, the combination with the frame, of shafts journaled on the frame, drive wheels rigid with the shafts, means for driving the wheels normally out of engagement therewith, and means for actuating said driving means to engage the wheels at different distances from the center thereof.

9. In a locomotive, the combination with the frame, of shafts journaled on the frame, drive wheels secured to the shafts, arms journaled on the shafts outside the drive wheels, a rod connecting the arms upon each side of the frame, means on the arms for engaging the drive wheels whereby to rotate the same, and means for moving said engaging means radially of the shafts whereby to engage 75 said wheels at different distances from their centers.
